Primary Examiner — Xavier Marti-Santos

CLAIM

The ornamental design for a hair curler as shown and described.

DESCRIPTION

FIG. 1 is a front elevational view of a hair curler showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a bottom, front and right side perspective view thereof; and,

FIG. 8 is a top, rear and left side perspective view thereof. The broken lines in the drawings illustrate portions of the hair curler which form no part of the claimed design.

1 Claim, 7 Drawing Sheets
